UNITED STATES PATENT OFFICE.

JOHN K. HARRIS, OF ALLENSTVILLE, INDIANA.

IMPROVEMENT IN BALING-PRESSES.

Specification forming part of Letters Patent No. 36,297, dated August 26, 1862.

To all whom it may concern:

Be it known that I, JOHN K. HARRIS, of Allensville, in the county of Switzerland and State of Indiana, have invented a new and useful Improvement in Presses for Baling Purposes; and I do hereby declare that the following is a full, clear, and exact description of the same, reference being had to the accompanying drawings, making a part of this specification, in which—

Figure 1 is a vertical section of my invention taken in the line $x x$, Fig. 2. Fig. 2 is a vertical section of the same taken in the line $y y$, Fig. 1; Fig. 3, a horizontal section of the same taken in the line $z z$, Fig. 2; Fig. 4, a diminished sectional elevation showing a modification of the same.

Similar letters of reference indicate corresponding parts in the several figures.

This invention consists in combining a follower with a system of levers, all constructed and arranged in such a manner that the follower may be made to serve the double purpose of a follower and a beater, the follower in the last-named capacity filling the press-box and compacting the material to be compressed therein, so as to be in proper condition for the subsequent pressing operation of the follower.

The invention is designed as an improvement on a press for which Letters Patent were granted to me bearing date August 20, 1861; and it is believed that by the present improvement the same end is attained by more simple and efficient means than those shown in the patented press alluded to.

To enable those skilled in the art to fully understand and construct my invention, I will proceed to describe it.

A represents an upright framing, which is composed of side pieces formed each of two vertical bars, $a a$, with a space, b , allowed between them, and B is a follower which works between said side pieces and within guide-strips c , attached thereto.

At the lower part of the upright framing A there is a press-box, C, which is formed by simply inclosing the lower part of said framing, as shown in Figs. 1 and 2.

On the upper end of the follower B there are placed side by side two sliding bars, $d d$. These bars have a horizontal position, and are

fitted and work between guides e , as shown clearly in Fig. 3; and they have each a bar, f , attached to them by a pivot, g , the upper ends of said bars being attached by a pivot, h , to a head, i , which is allowed to slide freely between two upright guides, $j j$, attached to the upper part of the follower at its center. When this head is drawn upward, the bars $d d$ will, owing to the latter being connected to the former by the bars $f f$, be drawn inward, so that their outer ends will be flush with the sides of the follower, and when the head i is depressed or forced down the outer ends of the bars $d d$ will be forced outward between the bars $a a$, which form the side pieces of the framing A.

D represents an upright shaft, which is placed in a suitable framing, E, connected with the framing A, and has a wheel, F, on its upper end, said wheel having a grooved periphery in which a segment-slide, G, is fitted loosely, and to which a cord or rope, H, is attached which passes underneath a pulley on the framing E, and over a pulley, J, on the top of the framing A, and is connected to the sliding head i of the follower B. The segment-slide G has a projection, k , attached to it, and to the under side of the wheel F there is secured a radial arm, l , which has a drop-catch, m , fitted in it.

To the framing E there is attached a pendant, n , having a double-beveled block, o , at its lower end. The wheel F and cord or rope H are designed to operate the follower B, when used as a beater to compact within the press-box C the substance to be afterward compressed.

The operation is follows: The horse or draft-animal is attached to a sweep, I, which is connected to the shaft D, and said shaft and wheel being rotated, the slide G will be carried around with the wheel F, in consequence of the catch m coming in contact with the projection k of slide G. The cord or rope H will therefore be wound around the wheel F and the follower B raised. The cord or rope, however, cannot be wound around the wheel F more than one revolution, as the lower end of the catch m will come in contact with the beveled blocks o once in each revolution, and the upper end of said catch will thereby be thrown out from the projection k of the slide G and the latter re-

leased, so that the follower B will fall by its own gravity and compact the substance within the box C. The follower B, therefore, it will be seen, is operated automatically, the catch *m* engaging itself with the slide G as soon as the former has passed the block *o*. This arrangement of the slide G and catch *m*, however, is not new, substantially the same arrangement being shown in my former patented invention, previously alluded to.

J J are two levers, which are attached at their upper ends by fulcrum-pins *q*—one to each side of the upright framing A. The lower ends of the levers J J have ropes K K attached to them, which pass around pulleys *r r* at the lower part of the press-box C, and are attached to a rope, L, which is connected to a collar or sleeve, M, placed loosely on the lower part of shaft D, and made to turn therewith when required by means of a slide-catch, *s*, fitted in the sweep I.

To each lever J there is connected by a hinge or joint, *t*, a pendent arm, N, the lower ends of which are fitted in slides O, placed between the vertical bars *a a* of the framing A. To each lever J there is also attached by a hinge or joint, *u*, a pendent bar, P. These bars P are above the arms N N, and are designed for raising the levers, or, rather, for throwing outward the lower ends of the same. When the follower B is used as a beater, the levers J are drawn close to the framing A, so as to be in nearly a vertical position; but when the pressing operation is to be performed, the lower ends of said levers are thrown outward from the framing by attaching the cord or rope H to the lower ends of the bars P, as shown in red in Fig. 1, and the shaft D turned. Other means, however, may be employed for adjusting these levers. When the levers J are thus thrown outward at their lower ends, the slides O will of course be raised, and as the head *i* of the follower B is left free, or has not the cord or rope H attached to it, or if attached not under

tension, the bars *d d* will be allowed to project outward from the follower, so as to form bearing-surfaces for the lower ends of the slides O. The sleeve or collar M on shaft D is then connected to the sweep I by adjusting the slide-catch *s*, and the shaft D being then rotated, the cord or rope L will be wound on the sleeve or collar M and the lower ends of the levers J J drawn toward the upright framing A, so that the arms N N will press down the slides O O, and the latter force down the follower B, in consequence of bearing on the ends of the bars *d d*. Thus by this simple arrangement it will be seen that the follower is made to perform the double function of a follower and beater and answer an admirable purpose. The press may be constructed at a very moderate cost, and it contains no parts liable to become deranged by use.

In Fig. 4, racks *a'*, of curved form, are shown attached to the lower ends of the levers J J, with a pinion, *b'*, gearing into them. The levers may be operated by this means equally as well as by the cords or ropes just described. I do not therefore confine myself to any particular means for operating the levers.

Having thus described my invention, what I claim as new, and desire to secure by Letters Patent, is—

1. The levers J J and arms N N, in connection with a follower and beater, B, arranged to operate as and for the purpose herein set forth.
2. The slides O O, connected with the arms N N of the levers J J, in connection with the sliding bars *d d* on the follower B, all arranged substantially as and for the purpose herein set forth.

JOHN K. HARRIS.
